UNITED STATES PATENT OFFICE.

ALFRED RICHTER, OF DOBERITZ, NEAR BERLIN, GERMANY, ASSIGNOR TO A.-G. FUR
HANDELS- UND INDUSTRIEWERTE GLARUS, OF GLARUS, SWITZERLAND.

REFRIGERATING APPARATUS OF THE ABSORPTION TYPE.

Application filed February 9, 1925, Serial No. 8,024, and in Germany December 14, 1924.

The invention relates to refrigerating apparatus of the absorption type and has for its object to provide an arrangement which will insure the convenient control and regulation of the apparatus by even an inexperienced attendant without possibility of damage or injury to person or apparatus, as from explosion due to improper manipulation of types of refrigerating apparatus now in common use.

In the accompanying drawing;

Fig. 1 is a view showing diagrammatically the invention in connection with a refrigerating apparatus,

Fig. 2 is a detail section of the valve,

Fig. 3 is a section on the line III—III of Fig. 2.

As shown in Figure 1 of the accompanying drawings, the apparatus consists of a boiler 1, a water separator 2, a condensing coil 3, an evaporator 4 and a cooling water reservoir 5. During the boiling period the refrigerating means, e. g. the ammonia, expelled from the heated boiler 1 in the form of vapour, passes through the pipe 6 to the water separator 2, from the latter through the pipe 7 into the condenser 3 and thence through the pipe 8 into the evaporator 4. In this way the ammonia is liquefied in the condenser 3 and again evaporated in the evaporator 4 by the latter absorbing heat from the surroundings e. g. from the interior of a refrigerating safe, into which the evaporator 4 has been built. As soon as the ammonia has been completely expelled from the boiler, the heat is cut off, whereupon it is cooled in a suitable manner, whereby a low pressure is produced in the boiler and the ammonia vapour is drawn back into the boiler 1. When this takes place the cooling of the condenser 3 (water supply) is preferably shut off.

It often happens however that steam is forced along with the ammonia vapours. As it is well known ammonia or another refrigerating means is dissolved in a liquid, preferably in water, and during boiling the ammonia is expelled from this solution.

Such apparatus therefore often require that liquids accumulated in the evaporator be drawn off, and for this reason it has already been proposed to employ a pipe which draws the liquid up, such pipe being connected at the lowest possible point of the evaporator and returned to the boiler in a suitable manner. If by cooling the boiler a

low pressure is produced therein and if the "drawing-up" pipe is connected to the boiler, the liquid deposit in the lower part of the evaporator is also drawn up by the low pressure, i. e. the deposit returns to the absorber.

In order that this drawing-up may be effected by the boiler itself it has already been proposed to connect this "drawing-up"-pipe to that conduit which otherwise is used for expelling and for drawing back the refrigerating means (ammonia and the like).

In Fig. 1 of the accompanying drawings 10 denotes the "drawing-up"-pipe connected to the lowest possible point of the evaporator 4 and, in order to clearly illustrate the arrangement, it is shown as passing upwards on the outside of the refrigerating safe which however would not be done in practice. This pipe 10 is at a point situated above the condenser 3 connected to the conduit 7. Care must be taken that the refrigerating means (ammonia or the like) does not enter simultaneously the condenser 3 and the "drawing-up"-pipe 10 during the ordinary running of the apparatus and for this reason a shut-off valve must be placed into the conduit 7 where it branches off to the condenser and to the pipe 10. Heretofore for this shut-off valve a three-way cock was chosen which has given rise to the greatest and most dangerous disturbances in the running of the apparatus. If the three-way cock was not attended to in the most careful manner and brought into one of its two end positions, but on the contrary it was left in an intermediate position the outlet for the boiled up ammonia gases from the boiler 1 to the condenser and evaporator was shut off during boiling. Consequently the pressure in the boiler, separator and conduit 7 due to the expansion of the ammonia gases became dangerously high and it has happened that such apparatus exploded.

It may perhaps be argued that by giving proper instructions, by marking the three-way cocks so as to indicate the end movement of the valve cone, and so forth, care could have been taken that such wrong adjustments with such disastrous consequences might be avoided. The invention is however based on the principle that all parts of the apparatus must be so constructed that the accidental neglect to properly adjust and manipulate the three-way cock as might readily

occur with inexperienced servants in domestic life cannot in any way endanger the apparatus and its surroundings. Since this intermediate member (shut-off valve) is such 5 an important factor in the safe operation of an otherwise efficient apparatus, it has been the object of the invention to construct this shut-off valve itself in such a manner that even its wrong manipulation can never en- 10 danger the apparatus.

Thus the invention consists therein that the shut-off valve in all possible positions of its cone or equivalent element and under all circumstances effects a communication be- 15 tween the boiler on the one hand and the evaporator on the other hand, in which case it is immaterial whether the connection is over the condenser or over the "drawing-up"- pipe. This alone gives the absolute guaran- 20 tee that in any position, proper or improper, of the shut-off valve, the expelled ammonia vapours pass from the boiler into the evaporator and thus into a space of a relatively low temperature which on the one hand cools 25 and liquefies these vapours and which on the other hand is sufficiently large for the expansion of them so that a dangerous increase of the pressure of the vapours is now once and for all avoided.

30 One mode of constructing such a shut-off valve is shewn diagrammatically and in section in Fig. 2 of the drawing. In said figure a cylindrical casing 14 is shewn having a reduced portion and being fitted with three 35 pipe connections. The port 15 is connected to the conduit 7 (Fig. 1), the port 16 to the pipe 10 and the port 17 to the conduit leading to the condenser 3. These pipe connections are welded together with the other con- 40 ducts or connected therewith in another suitable rigid and tight manner.

During the ordinary running of the apparatus the expelled refrigerating means is intended to pass through the port 15 and the 45 shut-off valve into the port 17 or to flow in a reverse direction when absorption takes place. On the other hand when drawing the deposit up the pipe 10 shall be connected to the boiler 1, while the condenser 3 is cut 50 out so that a direct flow from port 16 to port 15 takes place.

In accordance therewith these three pipe ports 15, 16 and 17 open into a common cylindrical chamber 18 partially fitted with a 55 thread 19 into which is screwed a double cone 20. This thread and eventually also the cone are fitted in one or several places with recesses 21 of a suitable depth and running in an axial direction.

60 It will be seen that when turning the double cone in the direction of the arrow 22 the cone 23 is forced against the seat 24 thereby closing an outlet opening from the chamber 18 into the port 16 and thus into the "draw- 65 ing-up"-pipe or from this pipe back into the

chamber 18. If however the double cone 20 is turned in the opposite direction, the cone 23 is lifted off its seat and the other cone 25 is forced against the seat 26 so that the passage is closed leading from the chamber 18 70 into the port 17 and thus into the condenser 3 and reversely from the condenser 3 back into the chamber 18.

The turning of the double cone 20 is for instance effected by means of a spindle 27 75 having a square head 28 on its outer end. The spindle 27 is by means of a suitable packing 29 arranged tightly within the casing 14, while a stuffing box 30 or the like is placed over the end of the spindle and 80 screwed into the casing.

In the position of the double cone 20 shewn on the drawing there is no connection between the port 16 and the boiler. The vapours can flow from the port 15 through the 85 chamber 18 to the port 17 and reversely by these vapours entering in the first instance the chamber 18 around the double cone 20 and then passing through the notches 21 in the thread of the double cone into the other 90 part of the chamber 18 and from here into the port 17 and reversely.

In the other end position of the double cone 20 in which the cone 25 is resting 95 against the seat 26 thus closing the passage in the port 17 and therefore also to the condenser 3, the vapours can pass from the pipe 10 into the port 16, from here directly into the chamber 18 and finally into the port 15 and thus into the absorber 1. 100

If now the shut-off valve 20 has been im- 105 properly operated and not been brought into one of its end positions but if it has rather been allowed to remain in an intermediate position it is obvious that the evaporator and condenser remain connected to the boiler 1. In this case none of the cones 23, 25 will 110

rest on their seat 24 or 26 and thus a free communication between the boiler on the one hand and the condenser or the evaporator on the other hand can take place. The wrong adjustment of the double cone 20 will then be recognized by a poor cooling or refrigerating effect but not too late to avoid damage by explosion of the apparatus. The in- 115 vention may naturally be carried out in different ways, and in a similar manner as it is done with the described and illustrated device prevent an improper operation of the controlling valve by giving the screw thread 120 19 a high pitch so that for instance a turning of the spindle 27 by 180° will suffice to cause one of the cones 23 or 25 to rest tightly on its seat, and one can thus by means of hand-mechanisms ensure a good handling of the valve in an easy manner.

I claim as my invention:

1. Refrigerating apparatus working on the absorption principle, comprising a generator-absorber, a condenser-evaporator, a 130

pipe for return solvent connected to said condenser-evaporator and leading to the generator-absorber, connecting pipes to the condenser-evaporator, a shut-off member for the solvent-returning pipe on the one hand and the connecting pipe to the condenser-evaporator on the other hand, said shut-off member closing in a fluid-tight manner in one end position the connection between the solvent-returning pipe and the generator-absorber and in its other end position closing the connection between the condenser-evaporator and the generator-absorber and in all its intermediate positions leaving always open a connection between the generator-absorber on the one hand or the solvent-returning pipe on the other hand and the condenser-evaporator.

2. Refrigerating apparatus working on the absorption principle comprising a generator-absorber, a condenser-evaporator, a pipe for returning solvent connected to said condenser-evaporator and leading to the generator-absorber, connecting pipes to the condenser-evaporator, a shut-off member for the solvent-returning pipe on the one hand and the connecting pipe to the condenser-evaporator on the other hand, said shut-off member closing in a fluid-tight manner in one end position the connection between the solvent-returning pipe and the generator-absorber and in its other end position closing the connection between the condenser-evaporator and the generator-absorber and in all its intermediate positions leaving open

a connection of sufficient cross-sectional area between the generator-absorber on the one hand and the solvent-returning pipe and the condenser-evaporator on the other hand, said shut off member including a chamber in communication with the solvent-returning pipe and the pipes leading to the generator-absorber and to the condenser, and a valve arranged in said chamber adapted in one of its two end positions to close the solvent-returning pipe and in its other end position to close the mouth of the pipe leading to the condenser.

3. Refrigerating apparatus as claimed in claim 2, characterized by the feature that the double valve comprises a double cone having a screw-threaded part which engages with an internally screw-threaded part of the chamber into which the connecting pipes to the generator-absorber and to the condenser, as well as the solvent-returning pipe, open, the said double cone also having one or more grooves parallel to the axis of its screw-threaded part, arranged in such a way that by rotating the double cone in one direction or the other, either the mouth of the solvent-returning pipe or the mouth of the connecting pipe to the condenser is shut off, while in all intermediate positions of the double cone a connection between all the pipes is open.

In testimony whereof I affix my signature.

ALFRED RICHTER.
